UNITED STATES PATENT OFFICE.

JOHN MONROE MOCK AND HOLLIE CARTMILL PRATHER, OF JEWETT, ILLINOIS.

ROAD-GRADER AND DITCHING-MACHINE.

No. 926,503.

Specification of Letters Patent.

Patented June 29, 1909.

Application filed October 14, 1908. Serial No. 457,681.

To all whom it may concern:

Be it known that we, JOHN MONROE MOCK and HOLLIE CARTMILL PRATHER, citizens of the United States, residing at Jewett, in the county of Cumberland and State of Illinois, have invented certain new and useful Improvements in Road-Graders and Ditching-Machines, of which the following is a specification.

13 This invention relates to excavators and has special reference to a device for grading roads and digging ditches.

An object of this invention is to accomplish the grading of a road in a short time 15 and in the greater efficiency of the work than is the ordinary method in effecting the same at the present time.

The invention has for a further object a machine of such construction that the dirt 20 may be removed from the side of the road and conveyed to the center thereof by passing the machine over one side of the road but two or three times to effect this result.

The invention has for another object the provision of a machine which is comparatively simple in structure and which will do the above described work efficiently and quickly.

Other objects and advantages will be apparent from the following description and it will be understood that changes in the specific structure shown and described may be made within the scope of the claims without departing from the spirit of the invention.

In the drawings forming a portion of this specification, and in which like numerals of reference indicate similar parts in the several views, Figure 1 is a front elevation of the machine, Fig. 2 is a rear elevation of the same, Fig. 3 is a side elevation of the right side of the machine, Fig. 4 is an opposite side elevation, Fig. 5 is a top plan view, Fig. 6 is a detailed and enlarged view of a section 45 of the conveyer belt employed, Fig. 7 is a fragmentary view of the combined plow and scoop employed in connection with this machine.

Referring to the drawings 10 designates 50 the frame of the machine which is provided with a rear stationary axle 11 and a forward axle 12 which is of considerably reduced length. Wheels 13 and 14 are disposed loosely upon the extremities of the axles 11 and 12. The wheel 14 upon the left side of the machine is keyed to a large sprocket 15

positioned adjacent the same which carries an endless chain 16 extending upwardly to pass over a small sprocket 17 mounted intermediately upon a transverse shaft 18 mounted in standards 19 and 20 formed upon the frame 10. The outer extremity of the shaft 18 is provided with a beveled gear 21 which meshes with and operates a second beveled gear 22 carried upon the extremity of a shaft 23 which is mounted in the outer extremities of two diagonally and transversely disposed runways 24 and 25. A shaft 26 is disposed across the lower extremities of the runways 24 and 25 to support the lower extremity of a conveyer belt 27 which is mounted upon the runways 24 and 25. The shafts 23 and 26 are each provided at their opposite extremities adjacent the inner faces of the extremities of the runways 24 and 25 with toothed wheels 28 which engage the conveyer belt 27 and guide the same in its motion. The conveyer belt 27 comprises two chains spaced apart and which are provided at the juncture of the links with rollers 29 which engage over the runways 24 and 25 to lessen the friction of the belt 27 while traveling over the same. The links 30 of the conveyer support across their inner faces a plurality of slats 31 which are flanged upon their outer faces at one edge and along the opposite end thereof in order to form a plurality of pockets. A bracket 32 is laterally extended from the frame 10 beneath the runways 24 and 25 upon which is pivotally supported a plate 33 for the purpose of directing the gravel and the like deposited by the conveyer 35 upon the road. The plate 33 is provided with a cable 34 secured to one of the outer corners thereof, which cable is extended 40 centrally where it passes through an eye 35 carried in the upper extremity of an arm 36 supported upon the frame 10 and extends to the forward extremity of the standard 20 where it is engaged about a shaft 37 rotatably mounted in the standard 20 and operated by a hand wheel 38 positioned upon the rear extremity of the shaft 37 and held from rotation by the tension of a leaf spring 39 positioned upon the base of the standard 45 20 and engaged against the periphery of the hand wheel 38.

At the forward right hand side of the machine a plow 40 which is carried upon the lower extremity of a scoop 41 is positioned and is adjusted vertically in the following manner. The scoop 41 is supported in a

small triangularly shaped frame 42 which is provided with three standards 43 which comprise substantially rectangular beams having racks 44 formed centrally and longitudinally upon their inner faces into which are engaged pinions 45 which are carried upon shafts 46 and 47, the shaft 47 of which is geared to the shaft 46 and co-operates therewith to raise and lower the beams or standards 43 to actuate the scoop 41. The shaft 46 extends rearwardly of the machine where it supports a gear 48 which is meshed with a pinion 49 carried upon a shaft 50 longitudinally disposed of the machine in a bracket 51. The shaft 50 is provided upon its rear extremity with a hand wheel 52 by means of which the plow 40 and scoop 41 are adapted to be raised or lowered according to the requirements. When the gravel is forced upwardly on the scoop 41 it is necessary to provide a feeder to conduct the gravel over the rear extremity of the scoop 41 and deposit the same evenly upon the conveyer 27. The feeder comprises standards 53 disposed in parallel and extended upwardly from the upper end of the scoop 41 where a shaft 54 is transversely disposed across the standards 53 to support a plurality of radially extended blades 55 the entire width of the scoop 41 and which extend downwardly when rotated into proximity with the upper surface of the scoop. The shaft 54 extends centrally beyond the standards 53 and supports a sprocket 56 which is disposed in alinement with a sprocket 57 mounted upon the inner extremity of the transverse shaft 18 and to which it is connected by a chain 58 for the purpose of imparting a rotary motion to the same.

The operation of the device is as follows: The machine is constructed of a width equal to approximately one-half of the width of a road and is adapted to be drawn along one side of the road where the plow 40 is engaged in the earth loosening the same, and conducting it to the conveyer 27 over the scoop 41. The feeder wings 55 engage the gravel and dirt as it is fed upwardly upon the scoop 41 and by reason of the wings 55 throw the gravel and dirt evenly upon the conveyer 27 upon which it is carried to the opposite side of the machine and deposited upon the plate 33 from which it is delivered to the central portion of the road.

It is preferable to have the plow 40 engaged only a short distance in the ground the first time the machine is passed over the same and to engage the plow 40 deeper into the earth at each operation of the machine thereafter.

The plow 40 and scoop 41, as before described are adjustable by reason of the standards 43 which carry the racks 44, and the pinions 45 meshing therewith which are operated by the shafts 46 and 47 through

the gears 48 and 49 which are set in motion by the operator through the hand wheel 52.

When one side of the road is graded the machine is passed over the opposite side in the opposite direction and is caused to deposit the earth taken up from the side of the road into the central portion of the road adjacent the earth deposited by the machine when actuated in the opposite direction.

When the earth is deposited upon the endless conveyer 27 the rollers 29 which support the conveyer upon the runways 24 and 25 greatly reduce the friction of the conveyer and enable the same to be driven so far as we are aware with an expenditure of less power than machines of this type heretofore constructed. By reason of the pocket formation of the slats 31 the earth is positively carried upon the conveyer 27 and the machine is rendered more effective in operation as it prevents the earth from sliding down and off of the conveyer from the right side of the machine on account of the diagonal positioning of the conveyer upon the machine.

What is claimed is:—

1. A device of the class described comprising a frame, an endless conveyer mounted transversely in said frame, a second frame adjustably disposed in the forward extremity of said first frame, a plow carried by said second frame, a scoop carried by said second frame in juxtaposition to said plow and a feeder disposed on said scoop for forcing material collected on said scoop onto said conveyer.

2. A device of the class described comprising a frame, a conveyer mounted transversely and diagonally on said frame, means for actuating said conveyer, a bracket carried by said frame extending laterally beneath the upper extremity of said conveyer, a plate hinged to said bracket, a cable secured in the outer corner of said plate, a standard centrally disposed on said frame a shaft mounted in said standard the inner extremity of said cable secured about said shaft, a hand wheel mounted upon the rear extremity of said shaft, a spring carried by the base of said standard impinged against said hand wheel for normally holding the same in rigid position and means for collecting and depositing earth upon said endless conveyer.

3. A device of the class described comprising a frame, a conveyer on said frame, a second frame adjustably disposed in the forward end of said first frame adjacent said conveyer standards disposed at the corners of said second frame, racks centrally and longitudinally positioned in the outer faces of said standards, a shaft longitudinally mounted in said first frame, a pinion disposed on said shaft for engagement with one of said racks, a second shaft transversely

disposed in said first frame, said second shaft
geared to said first shaft, pinions disposed
on said second shaft for engagement with
said racks, a gear disposed upon the rear
5 extremity of said first shaft, a bracket dis-
posed on said frame, a stub shaft mounted in
said bracket, a pinion carried by said stub
shaft for engagement with said gear carried
by said first shaft and a hand wheel carried
10 by said stub shaft for operating said second
frame.

4. A device of the class described com-
prising a frame, a conveyer transversely dis-
posed across said frame, pockets transversely
15 mounted on said conveyer an adjustable com-
bined plow and scoop carried at the front
end of said frame adjacent said conveyer
and a plate disposed beneath the opposite
20 extremity of said conveyer, said plate being
adjustable.

5. In a device of the class described the
combination with a frame and a conveyer
transversely disposed on said frame, of pock-
25 ets formed across said conveyer, means for
collecting and depositing earth upon said
conveyer and an adjustable plate positioned
beneath the delivering extremity of said
conveyer.

6. A device of the class described com-
30 prising a frame, runways diagonally dis-
posed across said frame, a conveyer mounted
over said runways, rollers disposed on said
conveyer for engagement with said run-
ways, pockets formed on said conveyer, a
35 plow mounted on said conveyer, a scoop dis-
posed at the upper end of said plow, said
scoop and said plow being adjustably mount-
ed on said frame and a feeder carried by said
scoop for feeding earth to said conveyer.

40 7. A device of the class described com-
prising a frame, a conveyer on said frame,
means carried by said frame for actuating
said conveyer, a second frame adjustably
disposed in the forward extremity of said
45 first frame adjacent said conveyer a plow

carried by said second frame, a scoop car-
ried by said second frame integrally formed
with said plow, a feeder disposed upon said
scoop at the upper end thereof and means
carried by said first frame for raising and
50 lowering said second frame.

8. A device of the class described comprising
a frame, a sprocket keyed to one of the
wheels of said frame, a transverse shaft
mounted on said frame, a sprocket disposed
55 on said shaft, a chain engaged over said
sprocket for imparting motion to said shaft,
a sprocket disposed upon the inner extremity
of said shaft, a conveyer mounted on said
frame, means disposed on said frame for
60 connecting said shaft with said conveyer
to impart motion to said conveyer an ad-
justable scoop disposed at the forward ex-
tremity of said frame, a feeder mounted on
said scoop, a sprocket carried by said feeder
65 and a chain disposed across said sprocket
on said feeder and said sprocket on the inner
extremity of said transverse shaft.

9. A device of the class described comprising
a body portion, a conveyer mounted on
70 said body portion, a plow carried by said
body portion, a scoop carried by said body
portion integrally formed with said plow
and adjacent to said conveyer, and a feeder
carried by said scoop, said feeder comprising
75 standards extended upwardly from said
scoop, a transverse shaft mounted in said
standards, a plurality of radially extended
wings carried by said shaft, said shaft ex-
tended beyond one of said standards and a
80 sprocket disposed on said shaft for engage-
ment with said body portion to actuate said
feeder.

In testimony whereof we affix our signa-
tures, in presence of two witnesses.
